WINDING MECHANISM FOR TIMEPIECES

Application filed March 14, 1929, Serial No. 347,024, and in Great Britain March 22, 1928.

This invention relates to devices for winding the springs of spring-driven clockwork mechanisms which are subjected to vibration. Examples of such clockwork occur in the 5 case of clocks mounted on the dashboards or other equivalent parts of motor cars, and also in the case of watches which are worn personally, such as wrist watches, and it is the object of the present invention to provide 10 a simple and reliable form of mechanism by means of which in particular such clocks or watches may be automatically wound and kept wound.

According to the present invention, the 15 automatic winding mechanism comprises a weight mounted so as to oscillate in response to the vibrations to which the clockwork is subjected, and connected to the spring winding arbor or other member by which the 20 spring may be wound up through a unidirectional device which includes one or more cords or threads encircling a pulley and normally kept under tension by means of a spring. Conveniently a mechanism may be 25 employed such as set forth and claimed in the specification of United States Patent No. 1,616,339, and conveniently may be applied to the type of clockwork mechanism which is wound through a going-barrel, and consequently in which the winding arbor is only 30 rotated in one direction during winding and at other times is prevented from rotation.

The oscillating weight is preferably mounted to execute its oscillations under the control 35 of one or more springs, so that either the whole weight, or at least some point on it, moves in a direction substantially normal to the axis of the spindle carrying the pulley, which is primarily driven through the cord 40 or cords attached to the weight. One end of a flexible cord, thread, or the like may be then connected to the said point on the weight and may pass around the pulley, its other end being connected to a spring, which may be anchored to a fixed point on the casing 45 or support of the clockwork, or may, in fact, be anchored to another point in the weight as long as it is maintained in tension when the weight is moving in one direction. The 50 purpose of the spring is to maintain a tension

on one end of the cord or thread when the weight moves in a given direction. As a matter of fact, a second cord or thread passing around a second pulley, or another part of the same pulley, in the same sense as the 55 first cord may be employed, having one end attached to the weight near the point at which the spring referred to above it attached, and having its other end connected to a spring also attached to the weight, the arrangement 60 being such that one of the cords serves to transmit driving impulses when the weight swings in one direction, and the other cord when the weight swings in the opposite direction. The pulley or pulleys and the 65 spindle on which they are fixed are then connected through reduction gearing to the spring winding arbor or other member the rotation of which winds the spring of the 70 clockwork.

It is preferable to provide means for preventing the clock from being overwound, and according to a further feature of the invention, a relieving mechanism is provided which may be operated when the spring of 75 the clockwork is fully wound either to prevent the weight from vibrating, or to prevent the transmission of its vibrations to the winding mechanism. This may depend upon the epicyclic gear principle being arranged so 80 that when the spring of the clockwork cannot be wound further, one of the wheels of the reduction gearing is driven slightly as an epicyclic or planet wheel, and results in a 85 braking or locking device being applied to the weight, or in relieving one or both of the threads or cords so that the oscillations of the weight are not transmitted to the winding mechanism.

In order that the invention may be clearly understood and readily carried into effect, some forms of winding gear in accordance with the invention will now be described merely by way of example with reference to the accompanying drawings, wherein:— 90

Figure 1 is an elevation of one form of winding gear looking along the axis of the winding arbor of the clock;

Figure 2 is an elevation at right angles to Figure 1, partly in section; 100

Figure 3 is an elevation of a modification showing a method of preventing the clock from being overwound, and which may be applied to the construction illustrated in Figures 1 and 2; and

Figures 4 and 5 are views corresponding to Figures 1 and 2 showing a modified arrangement wherein reduction gearing consists of a worm and worm wheel.

- 10 Referring first of all to Figures 1 to 3, a complete eight-day clock is illustrated at *a* mounted in the casing *u* and has the winding arbor *b* for its main spring extending through the rear plate. Although not shown, this 15 clock is of the type with a going-barrel, so that the arbor *b* has to be turned in one direction for winding the main spring, and is then held stationary while the clock is going. The arbor *b* is connected to an intermediate 20 spindle *c* by intermediate spur gearing consisting of a pinion *d* and a spur wheel *d*¹ having a ratio of 8:1, and again, the intermediate spindle *c* is connected to the driving spindle *e* by further spur gearing *f*, 25 again with a ratio of 8:1. The result is that the ratio between the driving spindle *e* and the winding arbor *b* is 64:1.

The vibratory weight consists of a weight *g* held between two side plates *h*, the latter 30 also having between them a pivot block *j* bearing the pivot *k*, which can rock in a bracket *l* of the casing. The weight *g* is thus suspended on two coiled tension springs *m* supported at their upper ends on the fixed 35 casing, and supporting at their lower ends pins *m*¹ extending from the side plates *h* of the weight *g*. If such a clock is carried, for example, on the dashboard of a motor car, the inequalities in the road surface will produce 40 vibrations which when transmitted to the weight *g*, will cause the latter to turn in a vertical plane about the pivot *k*, stretching the springs *m*.

There are also four pegs *n*¹, *n*², *n*³ and *n*⁴ 45 extending across the space between the plates *h* approximately above and below a pair of pulleys *o*¹, *o*² fixed to the spindle *e*. The pulley *o*¹ is encircled by a cord or thread *p*¹, and the pulley *o*² is encircled by a cord or thread 50 *p*². The arrangement is as follows:—The lower end of the cord *p*¹ is attached directly to the peg *n*³ and then, as seen in Figure 1, passes clockwise around the pulley *o*¹ and is fixed to the lower end of a tension spring *q*¹, 55 the upper end of which is anchored to the peg *n*¹. Again, the cord or thread *p*² proceeding from the upper end, which is fixed to the peg *n*², passes around the pulley *o*² also in a clockwise direction as seen in Figure 1, and 60 is then attached to the upper end of a coiled tension spring *q*², the lower end of which is fixed to the peg *n*⁴.

The device as described so far operates in the following manner:—When a swing is set 65 up in the weight *g*, it will be assumed that

the latter first moves downwards, extending the springs *m*. The tendency is to pull on the lower ends of the threads *p*¹, *p*², and to slacken the upper ends. Consequently the cord *p*¹ will impart a driving impulse to the pulley *o*¹ and tend to turn the spindle *e* anti-clockwise, as indicated by the arrow in Figure 1. The cord *p*² during this movement will remain ineffective. Then during the return upward movement of the weight *g*, the cord *p*² will come into action and will also turn the spindle *e* in the direction of the arrow in Figure 1, the cord *p*¹ in turn becoming ineffective.

Thus, the net result is that there is a driving impulse imparted to the spindle *e* in the counter-clockwise direction, no matter whether the weight *g* is moving up or down. The spindle *e* is therefore turned step-by-step in a clockwise direction, as shown by the arrow in Figure 1, and the spring arbor *b* is turned counter-clockwise in order to wind the spring. By use of the gear ratio shown and a given weight, it is possible to wind a motor car clock fully in a few miles, so that even if the car then remains stationary, the clock will continue to go.

So far no mechanism is described nor illustrated in Figures 1 and 2 for avoiding the winding action when the spring becomes fully wound. Such a mechanism, however, is shown in detail in Figure 3, which shows the winding arbor *b*, the intermediate spindle *c*, and the driving spindle *e*. The spindles *c* and *e* are journalled in a pair of plates *r*. They are arranged so that if they were not restrained, they could turn about the spindle *b*, and in fact the driving impulses applied to the spindle *e* would, unless provision were made otherwise, cause the small pinion *d* to travel as viewed in Figure 3 in a clockwise direction around the spur wheel *d*¹ with which it engages, in an epicyclic movement. In normal operation, however, this is prevented by a tension spring *s* anchored between the tail *r*² extending from one of the plates *r* and the casing *u* (see Figure 3). The spring *s* is sufficiently strong to prevent the above-described movement of the pinion *d* and to ensure that instead of this movement, the drive of the spindle *e* shall rotate the arbor *b* to wind the clock.

When, however, the clock spring becomes fully wound, its resistance to rotation, of course, increases very considerably, with the result that the driving effort on the spindle *e* can no longer rotate the arbor *b*, but instead appreciably stretches the spring *s*, allowing the pinion *d* to travel a little around the spur wheel *d*¹. The result of this is that when the plate *r* is moved, its tail *r*² abuts against the head of a sliding pin *t* so as to push the latter into engagement with a recess *t*¹ in the pivot block *j* of the weight *g*. The engagement of the pin *t* in the recess

t^1 obviously locks the weight g against vibration when the clock is fully wound. The parts are shown in Figure 3 in the normal position they take up allowing the clock spring 5 to be wound. When the clock spring is fully wound and the pin t engages in the recess t^1 in order to prevent the weight g oscillating, the clock will begin to run down a little, with the result that the spring s can 10 contract so as to pull the plate r back to the position shown in Figure 3. The pin t is withdrawn from the recess t^1 by the spring u^1 surrounding the pin t and placed between its head and the fixed bracket t^2 . 15 The result is that the weight g is freed and the whole automatic winding mechanism is put into action again. During the normal operation, the tail r^2 is latched by a ball catch r^1 . This ball catch r^1 is 20 provided with a spring (not shown) so that it holds the tail r^2 firmly until the clock spring is fully wound when epicyclic movement of the plates r begins. Similarly it prevents the plate r from being rotated too 25 far in the anti-clockwise direction as seen in Figure 3 under the action of the spring s when the weight g has been unlocked. This is desirable in order to prevent "hunting" or "chattering" of the locking mechanism."

In the modified form of construction shown in Figures 4 and 5, the general arrangement is just the same as in Figures 1 and 2, and wherever possible the same reference letters have been applied. The difference in detail, however, is that the double reduction gearing d, f is here replaced by worm gearing, which may, of course, have the same reduction ratio as in Figures 1 and 2. The arbor b carries a 40 worm wheel v , the worm w of which is fixed to the driving spindle e , which in this case is at right angles to the axis of the arbor b . The pulleys o^1 and o^2 , although turning in a 45 plane at right angles to that corresponding to Figures 1 and 2, are still driven in precisely the same way from the weight g .

It will be realized that the invention includes many departures from the particular examples described above. The coiled 50 springs q^1 q^2 , for example, may be replaced by blade springs or any other type of springs. Again, the weight may be mounted in a plane parallel to the axis of the pulleys o^1, o^2 , as shown in Figures 4 and 5, so that the weight 55 as a whole does not move away from the axis when it swings, but a particular point on the weight only moves towards and away from that axis.

Furthermore, different forms of mechanism 60 may be provided for preventing overwinding of the clock spring. For example, a clutch or other connection may be arranged between the weight and the winding arbor to be disengaged as by slipping when 65 the spring is fully wound. Finally, it will be

realized that the invention is not limited to 70 clocks mounted upon motor cars, nor indeed to any clocks, and naturally when applied to watches for personal wear, the whole mechanism will be similar to that already described, but on a much smaller scale.

I claim:—

1. Means for winding a clockwork mechanism comprising the combination of a weight 75 mounted to oscillate in response to vibration and a unidirectional device consisting of a pulley in driving connection with the spring of the clockwork mechanism, a flexible member encircling said pulley and having both of its ends anchored so as to move with said weight, and a spring inserted in the length of said flexible member to apply tension thereto.

2. Means for winding a clockwork mechanism comprising the combination of a weight 80 mounted to oscillate in response to vibration and a unidirectional device consisting of a pulley in driving connection with the spring of the clockwork mechanism, a pair of flexible members encircling said pulley in the same direction and both having their two ends connected to said weight, and springs each inserted in the length of one of said flexible members in order to maintain same in tension.

3. Means for winding a time-piece comprising the combination of a weight mounted to 90 oscillate in response to vibration, a pulley mounted for rotation, a reduction gearing interposed between said pulley and the winding arbor of said time-piece, a flexible member encircling said pulley and having both 95 ends anchored to said weight, and a spring inserted in the length of said flexible member to impart tension thereto.

4. Means for winding a time-piece comprising the combination of a weight mounted to 100 oscillate in response to vibration, a plate mounted to swing about the axis of the winding arbor of the time-piece, a pulley in driving connection with said winding arbor and rotatably mounted in said plate, a flexible member encircling said pulley and having 105 both its ends anchored to said weight, a spring inserted in the length of said flexible member to apply tension thereto, a gear fixed to said winding arbor, intermediate gears mounted in said plate to connect said first-named gear to said pulley, a spring attached to said plate to maintain the normal position of the latter during winding, and a member 110 mounted to move with said plate to lock said weight against oscillation.

In witness whereof I hereunto subscribe my name this 5th day of March 1929.

HUBERT LESLIE STRINGER.
